UNITED STATES PATENT OFFICE.

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA.

VACUUM LIFTING DEVICE.

1,294,103.

Specification of Letters Patent. Patented Feb. 11, 1919.

Application filed July 19, 1917. Serial No. 181,468.

To all whom it may concern:

Be it known that I, HALBERT K. HITCHCOCK, a citizen of the United States, residing at Pittsburgh, in the county of Allegheny and State of Pennsylvania, have invented certain new and useful Improvements in Vacuum Lifting Devices, of which the following is a specification.

The invention relates to vacuum lifting or holding devices particularly designed for use in handling glass sheets but not limited to use in that relation. It has for its primary objects, the provision of an improved vacuum lifting cup, (1) which works independently of the other cups which are used with it and whose leakage will not affect the other cups, (2) which has means for supporting the glass sheet inside the periphery of the block thus avoiding breakage incident to the air pressure, and (3) which is of simple durable construction and in which the wearing parts can be conveniently and cheaply replaced. One embodiment of the invention is illustrated in the accompanying drawings, wherein—

Figure 1 is a vertical section through the device and Fig. 2 is a bottom plan view of the device of Fig. 1.

The device comprises a casing consisting of two parts 1 and 2 between which parts the diaphragm 3 of rubber or other suitable material is clamped, the halves of the casing being secured together by means of the bolts 4. The lower edge of the part 2 is provided with the engaging lip 5 of rubber or other suitable material clamped in position by means of the annular ring 6 secured by the bolts 7. The lower portion of the casing 2 is also provided with a plate 8 having the perforations 9, 10, 11, 12, shown in plan view in Fig. 2.

The inner edge of the diaphragm 3 is clamped between the plate 13 and the ring 14, such ring being held in position by means of the bolts 15. The plate 13 is also provided with a hollow stem 16 lying in the cylindrical portion 17 of the casing part 1. This stem carries a cap 18 screw-threaded into the stem and provided with a buffer spring 19 adapted to engage the screw cap 20. The diaphragm is normally held in the position illustrated, by means of the relatively strong coil spring 21, and a passage 22 is provided whereby air under pressure

may be supplied to the chamber back of the 55 diaphragm 3.

The plate 13 is provided with projections adapted to fit down into the perforations 9, 10, 11 and 12 when the diaphragm is forced into its extreme forward position, 60 and the lower face of the plate is provided with a sheet 23 of relatively soft material which lies in front of the plate 8 when the diaphragm is in its extreme forward position.

In operation air is applied to the passage 22 causing the diaphragm to move forward prior to the application of the engaging lip 5 to the sheet of material to be engaged, such forward movement of the diaphragm 70 expelling the air from the cup on the front side of the diaphragm. The lip 5 is then pressed against the surface of the sheet of glass or other material which is to be engaged, and the air pressure released from 75 the passage 22 permitting the spring 21 to expand and carry the diaphragm to its rear-most position, as indicated in Fig. 1. This produces a relatively high vacuum to the front of the diaphragm and gives a secure 80 attachment of the cup to the surface engaged.

The provision of the perforated plate 8 with the corresponding projections on the plate 13 permits substantially all the air 85 to be expelled from the interior of the cup on the forward movement of the diaphragm, and the plate 8 is advantageous in that it provides a support for the sheet of material which is engaged. This is particularly important where the sheet is relatively thin or fragile. The soft surface 23 on the front face of the plate 13 avoids the danger of breakage, such as might occur if the plate 8 were forced down sharply upon the sheet 90 95 to be engaged. Since the vacuum is maintained by the spring each cup is independent of every other cup and any leakage which occurs past the lip of one cup will not affect the other cups. The device thus enjoys an advantage over a vacuum system in which the cups are all connected to one exhausting means and wherein the leakage of one of the cups permits the release of all of them. It will also be seen that the wearing parts of the device, that is the diaphragm and engaging lip, may be easily replaced and at a relatively small cost, the main body

portion of the apparatus being capable of use for an indefinite period.

What I claim is:

1. In combination in a vacuum lifting or holding device, a cup comprising an engaging lip and a movable member for expelling air from the cup when such member is moved forward, fluid operated means for forcing the said member forward, and a spring means for moving the said member to the rear.
2. In combination in a vacuum lifting or holding device, a cup comprising an engaging lip and a diaphragm for expelling air from the cup when the diaphragm is moved forward, means for applying fluid pressure for moving the diaphragm forward, and spring means for moving the diaphragm to the rear.
3. In combination in a vacuum lifting or holding device, a cup comprising a metal casing provided with an engaging lip at its forward edge, a diaphragm which divides the casing into two chambers, means for applying air pressure in the chamber behind the diaphragm to move it forward, and spring means normally holding the diaphragm in its rearmost position.
4. In combination in a vacuum lifting or holding device, a cup comprising a metal casing provided with an engaging lip at its forward edge, a diaphragm which divides the casing into two chambers, means for applying air pressure in the chamber behind the diaphragm to move it forward, and a spring also located in the chamber behind the diaphragm and adapted to move it to the rear.
5. In combination in a vacuum lifting or holding device, a cup consisting of a two-part casing, an engaging lip at the forward edge of one part of the casing, a diaphragm clamped at its edge between the parts of the casing and dividing it into two chambers, means for supplying air pressure behind the diaphragm to move it forward, and a spring for moving the diaphragm to the rear.
6. In combination in a vacuum lifting or holding device, a cup consisting of a two-part casing, an engaging lip at the forward edge of one part of the casing, a diaphragm clamped at its edge between the parts of the casing and dividing it into two chambers, means for supplying air pressure be-
- hind the diaphragm to move it forward, and a spring for moving the diaphragm to the rear, the spring being located in the chamber behind the diaphragm.
7. In combination in a vacuum lifting or holding device, a casing provided with a perforated plate at its front side and an engaging lip projecting forward of the plate, a movable member for expelling air through said plate when moved forwardly, spring means for moving said member to the rear, and means for applying fluid pressure to overcome the spring means and move said member forward.
8. In combination in a vacuum lifting or holding device, a casing provided with a perforated plate at its front side and an engaging lip projecting forward of the plate, a movable member for expelling air through said plate when moved forwardly, said member being provided with means for fitting into the perforations in the plate, spring means for moving said member to the rear, and means for applying fluid pressure to overcome the spring means and move said member forward.
9. In combination in a vacuum lifting or holding device, a casing provided with a perforated plate at its front side and an engaging lip projecting forward of the plate, a diaphragm dividing the casing in two chambers and provided with projections for fitting the perforations in said plate when the diaphragm is moved to forward position, spring means for moving the diaphragm to the rear, and means for applying fluid pressure to the chamber to the rear of the diaphragm to force it forward overcoming the spring means.
10. In combination in a vacuum lifting or holding device, a casing provided with a perforated plate at its front side and an engaging lip projecting forward of the plate, a movable member for expelling air through said plate when moved forwardly, said member being provided with means for fitting into the perforations in the plate, relatively yielding engaging means carried by the faces of said last mentioned means, spring means for moving said member to the rear, and means for applying fluid pressure to overcome the spring pressure and move said member forward.

HALBERT K. HITCHCOCK.
